United States Patent

Des. 237,723
Patented Nov. 18, 1975

237,723

CROSS WITH ROTATABLE RING

Sam S. Sweet, 1295 W. Miracle Mile 85705, and
Josephine M. Conte, 1030 E. Blanton Drive 85719,
both of Tucson, Ariz.

Filed Jan. 2, 1974, Ser. No. 429,963

Term of patent 14 years

Int. Cl. D11—02

U.S. Cl. D29—23 A

The figure shown on the accompanying drawing is a perspective view of a cross with rotatable ring showing our new design.

The back sides of both the ring and cross are flat and unornamented.

We claim:

The ornamental design for a cross with rotatable ring, as shown and described.
